GRINDING MACHINE

Stephen E. Woodbury and Stephen E. Woodbury,
Jr., Beverly, Mass., assignors to Reid Brothers
Company, Inc., Beverly, Mass., a corporation of
Massachusetts

Application January 26, 1942, Serial No. 428,174

4 Claims. (Cl. 51—92)

This invention relates to a grinding machine and more particularly to a surface grinding machine.

The invention has for an object to provide a novel and superior surface grinding machine which may be economically manufactured and assembled and is of improved construction embodying novel driving mechanism, whereby to enable the machine to operate in an accurate, positive and smoothly operating manner.

With this general object in view and such others as may hereinafter appear, the invention consists in the grinding machine and in the various structures, arrangements and combinations of parts hereinafter described and particularly defined in the claims at the end of this specification.

In the drawings illustrating the preferred embodiment of the invention, Fig. 1 is a plan view, with portions broken away, of a grinding machine embodying the present invention; Figs. 2 and 3 are detail views of driving connections to the cross feed mechanism, to be referred to; Fig. 4 is a front elevation, partly in cross-section, of the machine shown in Fig. 1; Figs. 5 and 6 are detail views in transverse and longitudinal cross-section respectively of a driving drum forming a part of the driving mechanism, to be referred to; Fig. 7 is a side elevation, partly in cross section, of the grinding machine embodying the present invention; and Fig. 8 is a wiring diagram illustrating the control mechanism for controlling the driving mechanism, as hereinafter described.

In accordance with one feature of the present invention, provision is made for operating the reciprocable work supporting table through connections from a reversing motor arranged to be controlled by the movement of the table. Provision is also made in the motor circuit for decreasing the starting torque of the reversing motor whereby to reduce the shock incident to the change in direction and to contribute in producing smoother table operation and also to reduce to a minimum excessive heating incident to rapid reversal of rotation of the motor. As a further provision for assuring smooth and substantially vibrationless table operation, the connections to the table may include steel bands or straps arranged to be alternately wound and unwound upon a drum, as will be described.

Referring now to the drawings, and particularly to Fig. 4, the grinding machine indicated generally at 10 is provided with a grinding

wheel 12 and a longitudinally reciprocable work supporting table 14. The work supporting table is mounted to slide longitudinally upon ways 16, 18 provided in a cross slide 20 which, in turn, is adapted to be moved transversely in ways 22, 24, formed in the top of a casing 26 mounted upon the base 28 of the machine. The grinding wheel 12 is mounted upon a spindle 13 and is independently driven by a spindle motor 15, as shown in Fig. 7.

The work supporting table 14 is arranged to be reciprocated through connections including a driving pulley or drum 30 and two steel bands or straps 32, 34, each of which is connected at one end to the driving drum, as illustrated in detail in Fig. 5. The other ends of the straps extend over idler pulleys 36, 38 respectively, and are connected to lugs 40, 42 depending from the opposite ends of the table, as shown in Fig. 4. The idler pulleys 36, 38 are rotatably mounted upon studs 44, 46 supported in the cross slide 20.

Provision is made for driving and reversing the rotation of the drum 30 to cause the straps 32, 34 to alternately wind and unwind on the drum to effect reciprocation of the table 14 through connections from a reversing motor 50 as shown in Figs. 1 and 4. The drum 30 is mounted upon and arranged to rotate with a driving shaft 52 journaled in suitable bearings 54, 56 mounted in the machine frame. The shaft 52 is provided with a gear 58 fast thereon which is arranged to mesh with a pinion 60 formed integrally with a clutch member 62 rotatably mounted and longitudinally movable upon a shaft 64. The clutch member 62 is arranged to be moved into operative engagement with a clutch member 65 fast on the end of a shaft 67 suitably journaled in a gear casing 70 formed integrally with the motor supporting bracket 72. The shaft 67 is provided with a worm wheel 74 fast thereon arranged to cooperate with a worm gear 76 secured to the motor shaft 78.

In the illustrated embodiment of the invention, provision is made for disengaging the movable clutch member 62 from the power driven member 65 when it is desired to move the work supporting table manually, and as herein shown, the clutch member 62 is arranged to engage a cooperating member 80 fast on the shaft 64, which latter is provided with a hand wheel 82 at its outer end. The shaft 64 is journaled in a bearing 83 formed in a bracket 84 detachably secured to the casing 26. The mov-

able clutch member 62 is moved longitudinally to engage and disengage the clutch connections 65, 80 by a shifter member 86 adapted to be actuated through connections to a hand lever 88, as illustrated in Fig. 1. The pinion 60 is made wide enough to cooperate with the gear 58 in either of its longitudinally movable positions. As herein shown, the clutch shifter unit, indicated generally at 90, is carried by the detachably mounted motor bracket 72 to form an assembled unit therewith.

From the description thus far, it will be observed that the detachable bracket 72 carries the motor driving mechanism and the clutch shifting mechanism as a completely assembled unit which may be conveniently assembled prior to attachment to the casing 26 of the frame. This construction saves time in the assembly operation, renders the parts more accessible for replacement and repair, and results in economy and expediency in manufacture. In assembling the unit, it will be observed that the shifter member 86, which may be forked, is arranged to be received in a grooved portion 92 of the member 62. The unit is attached to the casing 26 by screws 94.

Referring now to Figs. 1, 2 and 3, provision is made in the preferred embodiment of the invention for progressively advancing or retracting the longitudinally reciprocable work table in a transverse direction during the operation of the machine. As herein shown, the cross slide 20 is provided with a bracket 96 attached to and depending from the underside thereof. A square threaded screw 98, secured at one end to the bracket 96, is arranged to be received in an internally threaded bushing or hollow shaft which in turn is rotatably mounted in a hub 102 formed in the casing 26.

Provision is made for intermittently rotating the hollow internally threaded shaft 100 in either direction to effect transverse movement of the table during the operation of the machine. As herein shown, the hollow shaft is arranged to be rotated through connections including a crank member 104, a rack 106 connected to and arranged to be reciprocated by the crank, and a gear 108 loosely mounted on the hollow shaft and cooperating with the rack 106. The loosely mounted gear is formed integrally with a pawl carrier 110 upon which is mounted a double pointed pawl 112 arranged to cooperate with a square toothed ratchet 114 keyed to the hollow shaft, as illustrated in Fig. 2. Provision is made for adjusting the double pointed pawl 112 to engage either one or the other of the points with the square toothed ratchet, or to position the pawl in a neutral position. Such adjustment may be effected through a spring pressed ball arranged to be received in depressions in the carrier, as indicated at 116 in Fig. 2, and may be moved from one position to another by rotating the knob 118. A hand wheel 119 also secured to the hollow shaft 100 is provided to permit manual operation of the transverse mechanism when the pawl 112 is in neutral position.

In operation, when it is desired to effect intermittent rotation of the hollow shaft 100 in a counterclockwise direction, the pawl 112 may be positioned as indicated in Fig. 2 so that when the pawl carrier 110 is rotated in this direction by the reciprocating rack 106 and the gear 108, the pawl 112 in engagement with the ratchet will rotate the hollow shaft in a counterclock-

wise direction. On the return stroke of the rack 106, the pawl will slide over the ratchet teeth. It will be clear that when the pawl is positioned to engage the second point thereof with the square toothed ratchet, rotation of the hollow shaft 100 in the reverse direction will be effected. Thus it will be seen that the internally threaded hollow shaft 100 in cooperation with the square threaded screw is operative to effect transverse movement of the cross slide 20 and the table 14 supported thereon, in either direction during the operation of the machine. As illustrated in Figs. 1 and 2, the reciprocated rack 106 is received in a guide 120 formed integrally with a sleeve 122 loosely mounted upon the hollow shaft 100 to permit relative movement of the supporting sleeve 122 during the angular movements of the rack 106 as reciprocated by the crank 104.

Referring now to Figs. 1 and 3, the mechanism for rotating the crank member 104 will be described. As therein shown, the crank member is clamped fast upon the end of a stud 124, rotatably mounted in a bearing 126 formed in the bracket 84. The stud 124 extends from and is formed integrally with a pawl carrier 128 in which two pawls 130, 132 are mounted and arranged to cooperate with a square toothed ratchet 134. The square toothed ratchet 134 is formed integrally with and is arranged to rotate with the driving gear 58. As above described, the driving gear 58 is arranged to change its direction of rotation during the operation of the machine. Thus, in operation, when the ratchet 134 is rotated in a clockwise direction, the pawl 130, see Fig. 3, will be operative to rotate the crank through a predetermined stroke until the tail of the pawl engages a pawl stop 136 extending from the bracket 84, see Fig. 7, to disengage the pawl 130 from its ratchet 134. Thereafter, during the remainder of the clockwise movement of the ratchet 134, the other pawl 132 will slip over the ratchet teeth. When the direction of rotation is changed, the pawl 132 becomes effective to rotate the crank as above described, until it in turn is disengaged from the ratchet by the pawl stop 136. Thus it will be seen that each time the crank is rocked in either direction the rack 106 is reciprocated to effect rotation of the hollow shaft 100 in the desired direction as determined by the adjusted position of the double pointed pawl 112. The rack 106 is secured to the crank 104 in a T-slot 105 to permit convenient adjustment of the length of stroke.

From the description thus far it will be observed that the detachable bracket 84 carries the crank driving mechanism and the connections for manually operating the machine as a completely assembled unit which may be conveniently assembled prior to affixing the bracket to the casing 26. Thus, the assembly of this portion of the machine is facilitated, the parts rendered more accessible for adjustment or replacement and the structure results in economy in manufacture.

Provision is made for permitting lateral movement of the driving drum 30 on its shaft 52 during the transverse movement of the cross slide 20. As herein shown, the shaft 52 is provided with three raceways 140 in which ball bearings 142 disposed in the drum 30 are arranged to run. As shown in Fig. 6, the ball bearings are retained in the drum by spring wire rings 145 arranged to be received in grooves 144 provided

in the drum. The rings may be open to enable them to be contracted and forced into the grooves where they may again expand into a position to prevent escape of the ball bearing members from the drum. Thus, it will be seen that the bearing members 142 serve as a driving connection between the shaft 52 and the drum 30 and also permit lateral movement of the drum in a smoothly operating manner, thus reducing friction and tendency to bind on the shaft to a minimum. As shown in Figs. 1 and 4, the bracket 96, attached to the cross slide 20, is provided with arms 146, 148 arranged to embrace the drum 30 and to move it along the shaft 52 in alignment with the longitudinally reciprocable table 14 as the cross slide is moved transversely.

Referring now to Figs. 1 to 8, provision is made for controlling the reversible motor 50 to effect a change in direction of rotation thereof through connections from the reciprocable work table 14. As herein shown, a reversing switch 150 mounted in the cross slide 20 is arranged to be operated by dogs 152, 154, adjustably supported upon and movable with the table 14. The reversing switch comprises a slidingly mounted stud 156 arranged to be reciprocated by a pivotally mounted arm 158 which is received in a slot in the stud 156. An operating arm 160, fast on the pivot shaft 162 is provided with pins 164, 165, arranged to be engaged by the dogs 152, 154, respectively, at the end of the predetermined longitudinal movement of the table. The switch stud 156 is provided with contacts 168, 170 and in operation, when a dog engages the switch 150, it operates to first open the prevailing circuit to the motor 50 and then close a second circuit to operate the motor in a reverse direction. A handle 161 is also provided on the operating arm 160 to permit the switch to be manually operated when desired. A safety switch, indicated at 172, may also be provided to be operative to open the entire circuit in the event the dogs 152, 154 are removed or become loosened. As illustrated in Fig. 4, cam pieces 174, 176 supported on the underside of the table 14 are arranged to engage and depress the switch member 172 to open the circuit at contacts 178 when the table overrides or fails to engage the reversing switch 150. The reversing switch may and preferably will be of standard construction.

As illustrated in Fig. 8, the wiring diagram therein shown includes connections to the grinding head motor 45, and to the reversing motor 50. Stop and start switches 182, 184 are arranged to open and close a circuit to a primary magnetic switch 185 which closes the circuits to the grinding head motor and to the reversing motor at contacts 186, 187, 188 and 189. The reversing switch, indicated at 150 operates to alternately open one circuit and close another to the magnetic switches 190, 192 for alternately opening and closing the circuits to the reversing motor 50 at contacts 194, 195, 196, 197, whereby to reverse the direction of the current through the motor so that its direction of rotation is reversed. The safety switch is indicated at 172 and a manually operated switch 198 may also be provided for opening the circuit to the reversing switch 150. It will be observed that the wire 210 is preferably led through contacts 212, 214 of the reversing switch in order to open the circuit through all three wires 210, 216, 218 simultaneously when the on and off switch 220 is turned off.

The table driving motor 50 is preferably of

the squirrel-cage polyphase induction motor type and is started by placing the same directly across the line and is stopped and reversed by reversing the connections to two wires of the primary winding 200 of the motor at the time the motor is still operating at full speed in the original direction. This motor is required to develop considerable power since in addition to overcoming the friction load of the table it must also overcome the inertia load thereof during rapid starting and stopping as well as the inertia load of the motor rotor, which may be comparable in amount to the inertia load of the table. During the stopping operation the voltage developed by continued rotation of the motor in its original direction due to inertia after the connections to the motor have been reversed effectively adds to the applied voltage to increase the current instead of opposing the applied voltage as in motors under normal operation.

Standard motors have been found to take excessive current with resulting overheating under these conditions and to produce torque which is too high resulting in too rapid stopping and reversal with constant deleterious shocks and jars to the machine parts. Complicated control circuits such as those involving insertion of resistance into the motor circuit under starting and reversing conditions are not satisfactory because of added expense and also because of failure of the control system under rapid repetition of operation. Increasing the size of a standard motor does not solve the problem, as this increases the inertia load because of the larger size rotor required.

It has been found that the structure of the motor itself can be modified to reduce the starting and reversing current and torque. This may be accomplished by increasing the number of turns in each phase of the primary winding of the motor 50 for a given applied voltage so as to decrease the current as well as the torque during starting and reversing. In standard motors the number of turns in the primary winding is such that the flux necessary to develop a back voltage substantially equal to the applied voltage is just slightly less than that which will saturate the iron of the motor in the portions of the iron having maximum flux density. That is to say, in a standard motor the maximum flux is just slightly less than that which will pass the knee of the magnetization curve of the iron. By substantially doubling the number of turns normally employed for a given voltage and iron structure, for example using approximately 1 $\frac{3}{4}$ to 2 $\frac{1}{4}$ times the number of turns usually employed, the flux necessary to produce a back voltage substantially equal to the applied voltage is reduced, the flux being substantially inversely proportional to the number of turns in the primary winding. By employing a primary winding which results in a flux which is not substantially greater than one-half of that necessary to produce saturation it has been found that the motor starts and reverses smoothly without taking excessive current.

With the motor employed in the present invention in which the number of turns in the primary winding is increased, the lesser amount of flux causes the torque during starting and reversing to be materially reduced and as the speed is low under these conditions the internal power developed by the motor is relatively low. The total starting and reversing current is therefore materially reduced. This current may be con-

siderably greater than full load current under steady load conditions but is much less than that taken by standard motors having primary windings designed to operate with the iron adjacent the air gap nearly at saturation during periods of maximum flux. Thus the motors employed in the present invention do not overheat and also develop a relatively low reversing and starting torque, producing smooth operation of the machine without jar or shock. It will be seen that the motor forming a part of the present invention is particularly adapted for the operation of machines having reciprocating tables with the motor electrically connected directly to a power line and mechanically connected to the table without intermediate reversing mechanisms so as to start, stop and reverse the table by mere reversal of the electrical connections.

While the invention is particularly useful in connection with a grinding machine embodying a reciprocable work supporting table and driving mechanism including a reversing induction motor of the character described, nevertheless viewed in its broader aspects the invention may include other types of machines wherein a reversible element, either of the reciprocating, rotating, or oscillating type, is arranged to be driven by a reversing induction motor having the characteristics and in the manner above described.

While the preferred embodiment of the invention has been herein illustrated and described, it will be understood that the invention may be embodied in other forms within the scope of the following claims.

Having thus described the invention, what is claimed is:

1. In a grinding machine, in combination, a longitudinally reciprocable work supporting table, driving mechanism for reciprocating said table including a reversing motor of the induction type having a primary winding, an electrical circuit for said motor for connecting said primary winding directly to a power line to apply full line voltage to said motor during starting and reversing of said motor, a switch in said circuit for effecting reversal of said motor, means carried by said work table for operating said switch when the table is moved a predetermined distance in either direction, the primary winding of said motor being wound to produce a maximum flux in the iron of said motor not substantially greater than half that causing saturation

of said iron so as to provide a torque eliminating abrupt reversal and insuring smooth starting movement.

2. In a grinding machine, in combination, a reciprocable work supporting table, driving mechanism for reciprocating said table including a reversing motor of the induction type having a primary winding, means for automatically controlling the reversing of said motor to reciprocate said table, said means applying full line voltage to said primary winding during reversing of said motor, said primary winding being provided with substantially twice the number of turns which will produce a maximum flux in the iron causing saturation thereof, whereby the current taken by said motor is maintained below that which will cause overheating and the torque produced by said motor during starting and reversing is sufficiently low to eliminate abrupt reversal and insure smooth starting movement.

3. In a grinding machine, in combination, a reciprocable work supporting table, driving mechanism for reciprocating said table including a reversing motor of the induction type having a primary winding, means for automatically controlling the reversing of said motor to reciprocate said table, said means applying full line voltage to said primary winding during reversing of said motor, the primary winding of said motor being wound to produce a maximum flux in the iron of said motor not substantially greater than half that causing saturation of said iron so as to provide a torque eliminating abrupt reversal and insuring smooth starting movement.

4. In a machine tool, in combination, a work holding member and a tool member, one of said members being movable relative to the other member, driving mechanism for moving said one member alternately in opposite directions including a reversing motor of the induction type having a primary winding, means for automatically controlling the reversing of said motor to alternately drive said one member in opposite directions, said means applying full line voltage to said primary winding during reversing of said motor, the primary winding of said motor being wound to produce a maximum flux in the iron of said motor not substantially greater than half that causing saturation of said iron so as to provide a torque eliminating abrupt reversal and insuring smooth starting movement.

STEPHEN E. WOODBURY.
